STRAINER OR DRUM SNARE TENSIONING
MECHANISMCecil H. Strupe, Cleveland, Ohio, assignor to
WFL Drum Company, Chicago, Ill., a copart-
nership

Application August 9, 1946, Serial No. 689,383

4 Claims. (Cl. 84—415)

1

This invention relates to improvements in a strainer or drum snares tensioning mechanism and has for its main object to provide a simple, unitary mechanism of this type which includes a lever actuated means operable by the drummer to tension and slacken the drum snares and which includes also an adjusting element for determining the maximum degree to which the snares may be tensioned by operation of the lever aforesaid.

A further object of the invention is to provide a combined lever actuated and maximum tension adjusting means, all of which are embodied in a unitary compact and light weight mechanism mounted upon the shell or casing of a snare drum, and wherein the actuations of the lever will not affect the means for adjusting the degree of tensioning of the snares.

A suitable embodiment of the invention is illustrated in the accompanying drawings, wherein:

Fig. 1 is a fragmentary perspective view of a snare drum equipped with a mechanism constructed in accordance with the invention.

Fig. 2 is a central vertical radial sectional view, on an enlarged scale, showing a fragmentary part of the drum and the said mechanism mounted thereupon.

Fig. 3 is a fragmentary plan sectional view taken on the line 3—3 of Fig. 2.

Fig. 4 is a fragmentary plan sectional view taken on the line 4—4 of Fig. 2.

Fig. 5 is a fragmentary detail sectional view, on an enlarged scale, taken on the line 5—5 of Fig. 2.

Fig. 6 is a view in elevation, on an enlarged scale, of a non-rotatable collar of the mechanism.

Fig. 7 is an enlarged perspective view of the split spring washer employed.

The mechanism of this invention comprises a channeled bracket member 1 (Fig. 2) which is suitably mounted rigidly upon the shell or casing 2 of the drum between the ends of the latter in vertical alignment with the snares 3.

The latter are secured at their ends to plates 4, one of the latter being rigid with the shell or casing 2, and the other thereof being movable radially of the said casing.

In the instance illustrated, one of said plates 4 is movable through a slot 5 in the lower drum head tensioning hoop 6 of the drum and is connected pivotally with the outer end portion of the channeled rocking lever 7, the side flanges of which are pivotally connected between their ends

2

with the flanges of the bracket member 1 by means of a pivot element 8.

The other end of said lever 7 terminates in a cylindrical sleeve 9 extending perpendicularly of the web portion and tangentially of the flanges of said lever 7 with its axis substantially coincident with that of a screw threaded post 10 projecting from and secured suitably against rotation to the drum shell 2 through the web of the channeled bracket member 1 in the upper end portion of the latter.

Said sleeve 9 is equipped with a helically disposed cam slot 11 of arcuate length appreciably greater than shown in Fig. 3 and which terminates in very shallow recesses 12a which operate to prevent the lever 12 from moving from either limit of its movement otherwise than in response to manual actuation of a lever 12a.

Disposed over the said post 10 is a helical compression spring 13 upon which a cylindrical sleeve 14 is supported, the latter being provided with a smooth cylindrical bore through which the shank of the post 10 passes to constitute a bearing for the said sleeve 14.

The post 10 is provided with a key groove 15 to receive the key projection 16 of a washer 17 which bears normally upon the outer end of the sleeve 14 (Figs. 2 and 5).

A spring washer 18, shown in Fig. 7, is interposed between washer 17 and a sleeve nut 19 engaged with the post 10 and constitutes an adjustable stop member which limits the outward movement of the sleeve 14.

A spring 21 is disposed over the pivot element 8 and has its terminal arms 22 bearing upon the webs of the lever 7 and bracket member 1, respectively, and operates to maintain the inner wall of the cam slot 11 normally engaged firmly with the lever 12a secured rigidly to the sleeve 14 and projecting through the cam slot 11.

The spring 13 is normally under an appreciable degree of compression and its pressure against the sleeve 14 maintains the latter normally at the outer limit of movement and the spring washer 18 compressed against the inner end of the sleeve nut 19 which determines the outer limit of movement of said sleeve 14 to which the lever 12a is secured rigidly and removably.

The sleeve nut 19 is adjusted in position and cooperates with lever 12a and cam slot 11 to determine the degree to which the drum snares 3 will be tensioned when the end portion of the lever 7, connected with said snares, is disposed at the outer limit of its movement. Said lever 55 is moved to said limit responsively to swing of

the lever 12a upwardly from the position shown in Fig. 3.

Due to the fact that the post 10 is rigid with drum shell and that, therefore, the washer 17 cannot be rotated by frictional engagement with the sleeve 14, the sleeve nut 19 cannot be rotated by operations of the lever 12a particularly also because of the relatively high pressure exerted upon the inner end of said sleeve nut 19 by pressure of the spring 13 against the sleeve 14, washer 17 and washer 18.

The snares 3 may be of any desired type, but in the instant case, they are, preferably, of the helical wire type embedded along their end portions in the plates 4, as shown and described in application, Serial No. 635,265 now pending.

Wire snares will elongate to a greater degree than gut or straight wire snares, so in order that the mechanism of this invention may be applied to the latter types, the pitch of the cam slot 11 must be reduced to meet requirements.

In Fig. 3, the mechanism is shown to be opposed to the left-hand of the drummer and thus the lever 12a moved by a thrust movement of the left-hand, but, if disposed diametrically opposite to the position of Fig. 3, the lever 12a must be actuated by the right-hand and pulled toward the drummer to tension the snares.

I claim as my invention:

1. A snare tensioning mechanism comprising a lever pivotally connected between its ends with the drum shell, one end of said lever pivotally connected with the drum snares, a longitudinally grooved threaded post rigidly secured to the drum shell and projecting through said lever adjacent its other end, a sleeve mounted rotatably and slidably upon said post, a sleeve nut mounted upon the outer end of said post, a washer non-rotatably and slidably mounted upon said post between said nut and said sleeve, a compression spring interposed between the latter and the drum shell, a lever rigid with said sleeve, and a helical type of cam slot in the portion of the first-named lever adjacent to said sleeve through which the lever of the latter projects.

2. A structure, according to claim 1, wherein a second spring is engaged with said first-named lever and the drum shell to maintain said lever

normally in snare slackening position and operative in cooperation with said sleeve operating lever and the cam slot to perform the function of said compression spring in event of breakage of the latter.

3. Mechanism of the type specified comprising a channeled sheet metal rocking lever pivotally mounted between its ends upon the drum shell and pivotally connected at one end with the drum snares and equipped at its other end with a wall extending perpendicularly to said shell and provided with a helical cam slot terminating in extension portions extending angularly of said slot, a threaded longitudinally grooved post rigidly secured at one end to the drum shell and projecting at its other end through the outer wall of said lever, a cylindrical sleeve mounted rotatably and slidably upon said post, a lever secured rigidly to said sleeve and projecting through said cam slot, a sleeve nut engaged with the outer end of said post, a washer non-rotatably and slidably engaged with said sleeve and interposed between the latter and said sleeve nut, and a compression spring interposed between the said sleeve and the drum shell.

4. A structure, according to claim 3, wherein a channeled bracket is secured rigidly to the drum shell and a pivot member for the channeled lever passes through said bracket, and a V-shaped spring is mounted pivotally between its ends upon said pivot member and has the outer ends of its arms bearing upon the drum shell and said last-named end portion of said channeled lever, respectively.
